UNITED STATES PATENT OFFICE

EMIL FRENKLER, OF ARLINGTON HEIGHTS, ILLINOIS, ASSIGNOR, BY MESNE ASSIGNMENTS, OF ONE-HALF TO F. SPOONHOLTZ, OF DES PLAINES, ILLINOIS

GARMENT HANGER

Application filed March 14, 1931. Serial No. 522,565.

The present invention relates to garment hangers generally, and more particularly to hangers of this class which are especially suited to supporting a coat and trousers.

5 One object of the invention is to provide a garment hanger comprising separable main and auxiliary members which may be completely manufactured independently of each other and then readily assembled by the user, 10 or another, without the use of special tools.

Another object is to so design the composite hanger that the main member may be a complete hanger in itself, and the auxiliary member may be positioned or removed as de- 15 sired.

Another object is to provide main and auxiliary members such that the two may be assembled or disassembled merely by distorting the main member, which is made sufficiently resilient for the purpose, so as to 20 reduce its length to enable it to be entered at its ends into, or withdrawn from, retaining loops on the auxiliary member.

Another object is to so construct the auxiliary member that it may be used with a main member of well known and standard design, thus providing the new composite hanger merely by making the auxiliary member and putting it in place on the well known main 30 member.

Another object is to provide a simple and inexpensive structure which will carry a coat and trousers in good form, and will hold the trousers in proper position to keep the creases 35 therein.

Another object is to provide a hanger structure of the kind mentioned wherein all the parts, if desired, may be made of wire.

Another object is to provide a hanger 40 wherein the auxiliary member need not be resilient but may be rigid throughout, the resiliency for assembly being provided by resilient portions of the main member. In such case the rigid member need not be made 45 of wire, but may be composed of wood or other material provided with the necessary loops for receiving the ends of the main member.

With these objects in view, the invention 50 finds embodiment in a hanger having wire

arms united at shoulder points to a transverse member preferably also of wire, and preferably also integral with said arms, in combination with an auxiliary member having loops at its ends for receiving the ends of the 55 main member. The transverse member of the main hanger and the auxiliary member co-operate to engage trousers, or the like, carried by the hanger. In assembling the parts, the main member is distorted so as to reduce 60 its length and bring its ends toward each other far enough to enable them to be slipped into the loops of the auxiliary member.

These and other objects, features and advantages of the invention will be more fully 65 understood upon reference to the following detailed description taken in connection with the accompanying drawings, while the scope of the invention will be particularly pointed out in the appended claims. 70

In said drawings, Fig. 1 is a side elevation of the main member of the composite hanger structure, constructed and arranged in accordance with the present invention; Fig. 2 is a side elevation of the auxiliary member forming part of the composite hanger; Fig. 3 is an elevation of one end of the auxiliary member, a portion of the same being shown in section taken on a plane indicated by the line 3—3 of Fig. 2; Fig. 4 is an elevation of 80 the two members of the composite hanger occupying a position wherein the main member is contracted so as to reduce its length sufficiently to pass its ends into the loops of the auxiliary member; Fig. 5 is an elevation 85 of a modified auxiliary member, having an offset portion which enables the more ready placing of trousers, or the like, in position upon the hanger; Fig. 6 is a perspective view of a modified structure wherein the ends of the main member are bent outward to give support to coat shoulders and wherein the auxiliary member is provided with modified loops which will enable the more ready as- 90 sembling of this composite hanger; Fig. 7 is a sectional elevation of parts of the structure of Fig. 6, the parts shown in section on a plane indicated by the line 7—7 of Fig. 6; Fig. 8 is a perspective view of another form 95 of the invention wherein the main member 100

of Fig. 1 is employed with a modified auxiliary member; Fig. 9 is an elevational view of parts of this hanger, the section being taken on a plane indicated by the line 9—9 of Fig. 8; and Fig. 10 is a perspective view of one end of a modified auxiliary member showing the use of wire terminals and an intermediate wooden shank. Throughout these views like characters refer to like parts.

10 In said drawings, A designates the main member of the composite hanger, and B the auxiliary member. In the modifications, A' designates a main member similar to the member A, but having its ends bent and its center somewhat offset with reference to a plane through its ends, and B' designates an auxiliary member similar to the member B, but having a central depressed portion, B², an auxiliary member similar to the member B', but having its end loops modified so as to enable assembly upon the main member A', B³ designates a further modification wherein the auxiliary member has its end loops somewhat differently disposed, and B⁴, a composite auxiliary member partly composed of wood and partly of wire.

The main member A is preferably composed of wire throughout. In the instance illustrated, a single piece of wire is bent up 30 to form the entire member. As clearly shown, the ends of the wire are twisted at 10 to form a complete loop, and one of the wires is extended and bent so as to form the hook 11 by which the hanger may be suspended on 35 a support. The loop formed out of the wire comprises the inclined garment supporting arms 12, 13, the lower straight member 14, and the outer rounded ends 15, 16. Where a coat is hung upon the member A, the ends 15 and 40 16 extend into the shoulders, and the horizontal member 14 serves to carry the trousers, or other garment placed upon the hanger. The member A is of well known construction and, as before indicated, serves as the main element 45 of the composite hanger which I have devised.

The auxiliary member B is also preferably made of wire and includes an elongated portion 17, inclined end portions 18, 19, and end loops 20, 21. The end loops preferably lie in planes at right angles to the axis of the portion 17. These loops provide openings of sufficient size and properly positioned to receive the ends 15, 16, of the member A. 50 55 The way in which the end 16 fits into the loop 21 is clearly shown in Fig. 4.

Because of the distance between the ends 15, 16 being greater than the distance between the loops 20, 21, it becomes necessary in assembling 30 the two members to distort the main member A so as to bring the ends 15, 16 near enough together to pass them into the loops 20, 21, as shown in Fig. 4. There, the end 16 rests in the loop 21, and the end 15 is drawn 35 inward far enough to enable it to be slipped

into the opening of the loop 20. All of this will be clear from a consideration of Fig. 4. In order to bring the member A back to normal, it will be necessary to draw downward upon the transverse member 14 so as to bring it into its horizontal position. This will cause the end 15 to pass into the loop 20. Then both ends 15, 16 will remain in their loops 20, 21 until the member A is again distorted for removal of the auxiliary member B.

As before indicated, the auxiliary member B' is the same in construction as the auxiliary member B, except that the horizontal portions 22 have an intervening offset portion 23. The outer ends of the portions 22 have inclinations 18, 19 and end loops 20, 21, the same as the auxiliary member B. When the parts are assembled, the portions 22 lie adjacent to the member 14 of the main hanger, and the offset 23 allows the hand to be passed more readily between the main and auxiliary members, and thus allows trousers, or a like garment, to be brought more easily into position between the members 14 and 22, to clamp them and thus hold them suspended when the hanger is in use.

The main hanger member A' is made out of the member A. It has the same twisted portion 10 and hook 11. The inclined portions 24, 25 may be, if desired, bent into a different plane from the corresponding portions of the member A. When this is done, the intervening member 26 is also slightly bent, as indicated in Fig. 6. Such a bending of the portions 24, 25, 26, throws the ends 27, 28 slightly forward of the positions they would occupy, if the members 24, 25, 26 were all in the same plane, as in the case of the member A. To make the forwardly extending ends 27, 28, the ends 15, 16 of member A are bent outward, as clearly indicated in Fig. 6. These ends 27, 28 are desirable, in some instances, to more perfectly hold the shoulders of the coat placed upon the hanger.

The auxiliary member B² has horizontal portions 29 and an intervening offset portion 30. Its ends are like the ends of the member B', but the loops 31, 32 do not provide openings which are so fully enclosed. The portions which compose these loops 31, 32 are cut off so as to provide short hooks 33, 34. This change is made for the purpose of enabling the parts to be assembled with a less distortion than would be necessary were the loops the same as the loops 20, 21. The bent ends 27, 28 on the member A' prevent the latter's being distorted to the same extent as the member A. However, the short hooks 33, 34 permit the parts to be properly assembled upon a reasonable drawing upward on the transverse member 26 of the hanger A'.

The auxiliary member B³ is the same as the auxiliary member B, except for the end loops 35, 36. Here, the intervening portion 37 is

adapted to lie close to the intervening portion 14 of the main member A throughout its length, due to the fact that there are no inclined portions like the portions 18, 19 of the auxiliary member B. In this instance, as before, the loops 35, 36 are positioned in planes substantially parallel to each other and at right angles to the axis of the intervening portion 37. The parts A and B³ are assembled in the same manner as the parts A and B previously described.

In some instances, it may be desirable to use a composite structure for the auxiliary member, such as the member B⁴. The latter includes a central rod or piece 38 of wood or like material, and at its ends are loops, such as the loop 39, formed of wire, the same as the loops 35, 36. The wire 40 upon which the loop 39 is formed, obviously would extend but a short distance into the end of the member 38, as clearly indicated in Fig. 10.

It will be apparent that in carrying out my invention, still other alterations and modifications may be made without departing from the spirit and scope of the invention. I therefore do not wish to be limited to the particular forms illustrated and described, but aim to cover by the terms of the appended claims all those alterations and modifications which rightly come within the purview of my invention.

What I claim as new and desire to secure by a patent of the United States is:

1. A garment hanger comprising a pair of garment supporting arms and an intervening supporting member extending between said arms, and a clamping member co-operating with said intervening supporting member to hold trousers or the like thereon, said clamping member having angularly disposed loops at its ends for slipping over the ends of said arms when said ends are drawn toward each other, the distance between said loops being less than the normal distance between said ends.

2. A garment hanger comprising a resilient main hanger having supporting arms and an intervening supporting member, said arms and member being resilient and easily moved toward each other to draw in the ends of said main hanger, and an auxiliary member having end loops capable of receiving the ends of said main hanger when the latter is expanded into its normal position, the loops being nearer together than said hanger ends when in normal position.

3. An attachment for a wire garment hanger having garment supporting arms and an intervening supporting member, said arms and member being composed of a single piece of wire, which attachment comprises an elongated member having transversely disposed loops at its ends capable of being slipped over the ends of said hanger when the latter is distorted to bring its ends inward to a

dimension less than the distance between said loops.

4. A garment hanger comprising a main member and an auxiliary member, said main member comprising a single wire bent into an elongated loop having angular end portions serving as garment shoulder supports, said auxiliary member comprising a single length of wire having angularly disposed loops at its ends, said loops being a distance apart less than the length of said main member and being adapted to fit over the angular end portions of said main member when the latter is distorted to bring its end portions near enough together to enter the loops of said auxiliary member.
